UNITED STATES PATENT OFFICE.

PAUL F. W. C. KRIPPENDORF, OF LYNN, MASSACHUSETTS, ASSIGNOR TO KRIPPENDORF KALCULATOR COMPANY, OF PORTLAND, MAINE, A CORPORATION OF MAINE.

CARD FOR USE IN COMPUTING STOCK.

Application filed June 20, 1919. Serial No. 305,553.

To all whom it may concern:

Be it known that I, PAUL F. W. C. KRIPPENDORF, a citizen of the United States, residing at Lynn, in the county of Essex and 5 State of Massachusetts, have invented certain Improvements in Cards for Use in Computing Stock, of which the following description, in connection with the accompanying drawings, is a specification, like reference characters on the drawings indicating like parts in the several figures.

This invention relates to a card for use in computing stock and is herein illustrated as embodied in a card designed to be used in 15 connection with a calculating machine such as that shown in Patent No. 1,212,231, granted to me on January 16, 1917.

This machine is adapted to be manipulated to indicate the amount of leather 20 which will be required to allow for the cutting, including waste, of a given number of uppers for shoes of a selected style and of different widths and sizes. Briefly, the manner of using the machine is as follows: The 25 amounts of stock required for cutting a hundred uppers for a certain style of shoe of a standard size and width from a number of different leathers are computed beforehand and the data placed upon a card which is 30 furnished to the operator of the machine. There is also furnished to the operator a list of the number of shoes of the sizes and widths of the particular style which is to be made, together with the kinds of leather 35 which are to be used. For example, let it be supposed that a woman's whole-quarter blucher shoe is to be manufactured having a cut-off vamp, the entire upper of which, including the top, vamp and tip are to be 40 cut from Russia calf. By inspecting the card, the operator will find a number, for example 292, which represents the number of square feet of that particular kind of leather which will be required for the cutting 45 of one hundred pairs of shoes of standard size and width, say 5D. This number the operator uses as a constant in the calculating machine, and, by manipulating certain parts of the machine in accordance with the data concerning the sizes and widths of 50 shoes which are to be manufactured, gets the total number of square feet of Russia calf which will be required for the cutting of all

the uppers. A copy of a card such as has been referred to above and a complete description of its use in connection with the machine will be found in the patent referred to above.

It is very desirable in a shoe factory that the operator of the machine and the cost accountant should know exactly what is the style of shoe to which the numbers refer. Accordingly it has been customary to print upon each card the style, for example "Women's whole-quarter blucher," but such a description is often incomplete and therefore misleading. All women's whole-quarter blucher shoes are not alike since they may differ in height or in the curvature of certain parts or in various other details, any of which may have an influence to increase or to decrease the amount of leather required for cutting the uppers.

According to one feature of the present invention there is provided on the card, and 75 preferably on the back thereof, a skeleton figure of a shoe or other article having guiding marks thereon to aid in the filling in of the figure as may be desired to illustrate not only the style of the particular article to 80 which the numerals refer but variations in the style. With such a card it is possible to see at a glance exactly the article to which the numerals refer, a result which is almost impossible to secure by any printed description. The computer (in this case the operator of the machine) and the cost accountant are thus provided with definite 85 descriptions of the articles to which the numerals on the various cards refer. On the 90 illustrative card three skeleton figures are provided, one for women's high-heeled shoes, one for women's low-heeled shoes and one for men's shoes so that the same card may be used in factories making any one of these 95 three styles.

Referring now to the accompanying drawings,—

Fig. 1 shows the front of a card in which the present invention is embodied, said card 100 having been filled in to indicate the amount of stock required from which to cut the upper of a certain woman's whole-quarter blucher shoe.

Fig. 2 shows the back of the same card, 105 the skeleton figure of the woman's high-

heeled shoe having been filled in to illustrate the shoe to which the numerals refer, and

5 Figs. 3, 4, 5 and 6 show skeleton figures filled in different ways.

Referring first to Fig. 1, under the general heading of "Top" there are three columns, the first of which is a series of figures 21 to 32, inclusive. These figures represent kinds 10 of leather such as mat calf, suede, mat goat, etc. The names may be printed if desired, but the figures have been found in practice to be preferable. The second column is headed "Plain" and is to be used when a 15 shoe having an unfolded top is being manufactured. The third column is headed "Fold" and the numerals 175 to 265 which have been filled in indicate the number of 20 square feet of stock required for cutting one hundred tops, which are to be folded, from the different leathers indicated by the figures 25 21 to 30. In the present example the tops are to be folded and are, for a six-inch whole-quarter blucher women's shoe; and it will require 175 square feet of mat calf, 185 square feet of suede, etc., to cut them.

Under the general heading of "Cut off vamp" there is first a column containing 30 printed figures 1 to 12, inclusive. These figures represent different kinds of leathers such as patent side, patent colt, gun metal side, gun metal, Russia calf, kid, ooze, etc. As in the case of the "Tops" the names of the leathers may be printed if desired. 35 Under the "Cut off vamp" heading are two sub-headings "No tip" and "Tip", and each of these has under it a column marked "Plain" and "Fold". The first column of numerals which have been filled in (50 to 40 75) indicate the number of square feet of stock required for cutting one hundred cut-off vamps from the different leathers indicated by the figures 1 to 10. The second column of filled in numerals (66 to 91) indicates the number of square feet required for 45 cutting both the cut-off vamp and the plain tip. To the right of the heading "Cut off vamp" is another heading "Whole-toe vamp" having under it various sub-headings 50 under which no numerals have been placed. Near the middle of the card appears the heading "Whole shoes", under which two columns have been filled in with numerals, one column beginning with 212 55 and ending with 327 and the other beginning with 228 and ending with 343. At the lower left-hand portion of the card appear several headings the spaces opposite which have not been filled in. It is believed to be 60 unnecessary to explain in detail just what each heading means, since from the description which has been given above, their meanings should be obvious and since different headings may be adopted if desired. 65 An explanation of the meaning of the nu-

merals 175, 50 and 66 has been given. It will be sufficient to state that the numeral 212 indicates that if the top and the cut-off vamp are cut from the same lot of patent side there will be required 212 square feet 70 for one hundred pairs and that if the top, cut-off vamp and plain tip are all cut from the same lot of patent side, 228 square feet will be required for one hundred pairs. It will be noted that if only the tops were cut, 175 square feet would be required, and that if only the cut-off vamps were cut, 50 square feet would be required. It might seem that cutting them both from the same lot of patent side would make no difference in the 75 amount required, which would consequently be 225 square feet. This is not the case, however; and only 212 square feet would in such case be required since it is more economical to cut large and small pieces from 80 the same skin.

Referring now to Fig. 2, it will be noted that there are shown three skeleton figures, the first of a woman's high-heeled shoe, the second of a woman's low-heeled shoe and the third of a man's shoe. The first skeleton figure has been filled in to show a woman's six-inch whole-quarter blucher with a cut-off vamp; and this is the shoe to which the filled in numerals on the other side of the 90 card refer.

All of the skeleton figures have upon them guide marks which will now be described. Referring more particularly to the second figure, the guide marks in the form of the dashes 1, 3, 4, 5, 6, and 7, together with the intermediate dot 2, if properly connected, would indicate a whole vamp; the marks 8, 9 and 10, if properly connected, would indicate an oxford; the marks 1, 2, 105 11, and 8 if properly connected would indicate a circular fox oxford; the guide marks 12 and 13, if properly connected, would indicate a whole vamp with a tip; and the guide marks 14 and 15 if properly connected 110 would indicate a cut-off vamp. The marks in the forms of pairs of dots at the upper parts of the figures are used to indicate the height of the shoe in inches.

In order to display the possibilities of 115 these skeleton figures, four of them have been filled in (see Figs. 3, 4, 5 and 6 of the drawings) to illustrate respectively a seamless fox oxford, a circular fox oxford, a whole-quarter blucher shoe and a whole-quarter finger fox blucher shoe with a cut-off vamp and a tip. By comparing Fig. 5 of the drawings with the filled-in figure in Fig. 2 of the drawings, the ease with which variations in style which would be difficult to distinguish by a printed description, may be shown will be appreciated. Both illustrations show a whole-quarter blucher shoe, but the shapes of the wing on the vamps are different in the two cases and different 120 125 130

amounts of leather would be required to cut them out even if they were alike in all other respects. Hitherto a great deal of confusion has occurred because of this difficulty in distinguishing one shoe from another on the card. For example, two cards might have on them the description "Women's whole-quarter blucher shoe," but the data might be different in the two cases. The cost accountant sees that one card calls for a certain amount of leather and that the other card calls for a greater amount. He assumes that there is a mistake somewhere, for the cards appear to describe the same shoe; and it may happen that he is obliged finally to find the sample shoes themselves before he gets the matter straightened out. The same sort of impression may confront the foreman of the cutting room and cause dispute between him and the operator of the calculating machine as to whether the proper amount of leather has been allowed to the cutters. With the present invention mistakes of this sort do not occur, since the filled-in figure shows at a glance just the style of shoe to which the numerals refer.

Throughout the specification the word "card" has been used, but obviously a sheet of paper would serve the purpose, and it should be understood that the word "card," as used throughout the claims, is intended to include tags, sheets and similar suitable articles. And although the card has been described as used in connection with a computing machine it should be understood that this has been done to promote clearness and that the invention is not limited to the manner of use which has been described.

Having thus described my invention, what I claim as new and desire to secure by Letters Patent of the United States is:

1. A card for use in computing the amount of stock required for the manufacture of an article having thereon a skeleton figure including guide marks which may be filled in according to the marks to illustrate the style of the article, and data showing the amount of stock required for a given number of articles of the illustrative style according to the kind of stock used.

2. A card for use in computing the amount of stock required for the manufacture of an article having thereon a skeleton figure provided with guide marks located to facilitate filling in the figure in any one of several ways so as to illustrate a selected style of article, and spaces provided with indicia to re-

ceive entries showing the amount of stock required for the selected style.

3. A card for use in computing the amount of stock required for cutting out shoe parts, having a skeleton figure including guide marks which may be filled in according to the marks to illustrate the style of shoe desired and spaces provided with indicia to receive entries showing the amount of stock required for a given number of shoes of the style illustrated.

4. A card for use in computing the amount of stock required for cutting out shoe parts having thereon a skeleton figure provided with guide marks which may be connected as may be desired in a selected way to show a shoe of a desired style, and spaces provided with indicia to receive entries showing the amount of stock required for a given number of the illustrated shoes according to the kind of stock used.

5. A card for use in computing the amount of stock required for cutting out shoe parts, having thereon a skeleton figure provided with guide marks located to facilitate filling in the figure in any one of several ways so as to illustrate a selected style of shoe, and spaces provided with indicia to receive entries showing the amount of stock required for the selected style.

6. A card for use in computing the amount of stock required for cutting out shoe parts, having on one side a skeleton figure provided with guide marks located to facilitate filling in the figure in any one of several ways so as to illustrate a selected style of shoe, and on the other side spaces provided with indicia to receive entries showing the amount of stock required for the selected style.

7. A card for use in computing the amount of stock required for cutting out shoe parts having thereon a skeleton figure of a shoe provided with guide marks located to facilitate filling in the figure in any one of several ways so as to illustrate a selected style of shoe.

8. A card for use in computing the amount of stock required for cutting out shoe parts having thereon a plurality of figures of shoes of different types each provided with guide marks located to facilitate filling in the figures in any one of several ways, any one of which may be filled in to illustrate the style of shoe desired.

In testimony whereof I have signed my name to this specification.

PAUL F. W. C. KRIPPENDORF.
